United States Patent Office

Des. 204,365

Patented Apr. 12, 1966

204,365

CLEANING MACHINE

Enrico A. Trombetta, 1787 W. 26th St., Erie, Pa.

Filed July 2, 1965, Ser. No. 86,014

Term of patent 14 years

(Cl. D9—2)

The figure is an isometric view of a cleaning machine showing my new design.

The sides are substantially identical. The rear of the cleaning unit is plain.

I claim:

The ornamental design for a cleaning machine, as shown and described.
